PLAYGROUND CLIMBER WITH A REPRESENTATION OF A FROG'S HEAD

Robert S. Wormser, Ocala, Fla., assignor to
Game Time, Inc.

Original design application Feb. 23, 1973, Ser. No.
335,070. Divided and this application Oct. 16,
1974, Ser. No. 515,176

Term of patent 14 years

Int. Cl. D21—03

U.S. CL. D34—5 H

FIG. 1

FIG. 4

FIG. 2

FIG. 3

FIG. 1 is a perspective view as taken from the front and right side of a playground climber with a representation of a frog's head in accord with my new design;

FIG. 2 is a front elevational view of my new design;

FIG. 3 is a side elevational view as taken from the left of FIG. 2, the opposite side being the mirror image thereof; and

FIG. 4 is a top plan view of my new design.

This application is a divisional application of design application Ser. No. 335,070, filed Feb. 23, 1973, entitled Playground Climber Representing a Frog.

I claim:

The ornamental design for a playground climber with a representation of a frog's head, substantially as shown and described.
